UNITED STATES PATENT OFFICE.

MARY N. ESTERBROOK, OF NEW YORK, N. Y.

TAPE-NEEDLE.

SPECIFICATION forming part of Letters Patent No. 655,333, dated August 7, 1900.

Application filed May 8, 1900. Serial No. 15,953. (No model.)

To all whom it may concern:

Be it known that I, MARY N. ESTERBROOK, of New York, State of New York, have invented a certain Improvement in Ribbon-Needles, of which the following is a specification.

This improvement consists of a ribbon-needle made of a strip of metal or other suitable material, preferably, although not necessarily, 10 tapered, smooth, and generally rounded at one end, provided with one or more teeth at its opposite end, and provided with a transverse slot near its toothed end. In use a ribbon or tape is drawn through the slot, turned backward, 15 and caught on the toothed end of the needle. By this device the strain of the part of the ribbon caught on the toothed end is lessened by the frictional hold upon the ribbon of the edge of the slot, which engages the bight of 20 the ribbon.

The accompanying drawings, illustrating two examples of the invention, are as follows:

Figure 1 is a side view of a ribbon-needle intended for carrying a comparatively narrow ribbon and provided with a single tooth at 25 its toothed end. Fig. 2 is a side view of a needle intended for a wider ribbon and embodying the modification, which consists in providing the toothed end of the needle with 30 a plurality of teeth. Fig. 3 is a view of the edge of the needle, showing the ribbon attached.

For the sake of clearness of illustration the drawings represent the ribbon-needle as 35 magnified in size.

In carrying the invention into practice the

needle is usually made of suitably thick sheet metal. The shank *a* of the needle is usually tapered and has its smaller end *b* smoothly rounded. Near its larger end it is provided 40 with a transverse slot *c*. At its larger end it is provided with a single pointed extension or tooth *d*, if it be intended for use with a narrow ribbon, as shown in Fig. 1. When intended for use with a wider ribbon, the 45 needle may be correspondingly widened, the slot *c* elongated, and the toothed end provided with a plurality of sharp-pointed extensions—as, for example, with the two teeth *d* *d'*. (Shown in Fig. 2.)

In use the ribbon *e* is drawn through the slot *c* and turned back, forming the return-bend *e'*, which is caught on the toothed end of the needle, as illustrated in Fig. 3. The advantage of this mode of attaching the ribbon is that the part of the return-bend *e'* 55 caught on the toothed end of the needle is not required to bear the entire strain when the ribbon is being drawn through the fabric, because a considerable portion of the strain 60 is taken by the edge *c'* of the slot seated in the bight *e* of the return-bend.

What is claimed as the invention is—

A ribbon-needle composed of a strip of suitable material smooth at one end and toothed 65 at its opposite end and provided with a transverse slot near its toothed end.

MARY N. ESTERBROOK.
